UNITED STATES PATENT OFFICE.

ADAM A. SERVA, OF CANTON, OHIO, ASSIGNOR TO THE UNITED ELECTRIC COMPANY,
OF CANTON, OHIO, A CORPORATION OF OHIO.

SUCTION CLEANER.

Application filed October 15, 1921. Serial No. 507,896.

The invention relates to air cleaners of the suction type, for carpets, rugs, floors and the like; and the object of the improvement is to supplement the suction of air through the carpet or under the lips of the cleaner, by a blast of air acting upon the carpet or the surface of a floor, within the mouth of the cleaner.

Difficulty is experienced in picking up threads, lint and other light, fluffy articles, by the pressure and volume of air usually available in portable electric machines, and it is customary to supplement the same by the use of a rotary brush operating in the mouth of the machine. The present invention involves the use of a suction fan and a separate smaller fan to produce a blast of air to impinge and scour the objective surface within the mouth of the cleaner, without the use of a brush and without materially modifying the suction action of the larger fan.

The invention may be embodied in the various forms and arrangements of cleaners illustrated in the accompanying drawings, forming part hereof, in which:

Figure 1 shows a preferred arrangement of the fans below the motor case, with the suction fan below and the blast fan above a common partition;

Fig. 2, an arrangement of the fans and an intervening air chamber below the motor case, with the suction fan above the blast fan, to reverse the direction of the blast within the mouth of the machine; and

Fig. 3, a plan view of the elongated mouth such as shown in Fig. 2.

Similar numerals refer to similar parts throughout the drawing.

Referring to Figure 1, the machine includes a fan case 1 formed with a transversely elongated head 2 on its forward end, a cylindric extension 3 on its rear end, and a motor 4 centrally mounted thereon.

The motor spindle 5 extends downward into the fan case, and a blast fan 6 and a relatively larger suction fan 7 are secured thereto on opposite sides of a partition wall 8 extending through the fan case.

A transversely elongated mouth 9 in the head of the machine is provided with lips 10 and 10' adapted to contact with the objective carpet or surface to be cleaned, and a V-shaped partition wall 11 is provided in the head of the machine extending longitudi-

nally of the mouth, which terminates in an edge 11' within and adjacent and above the plane of the lips, thus dividing the mouth into a forward transverse slot or channel 12 and a relatively larger rear transverse slot or channel 13; the former channel communicating with the discharge outlet 14 of the blast fan, and the latter channel communicating with the inlet 15 of the suction fan.

A tubular wall 16 forms a channel 16' within the rearward extension of the fan casing, and communicates at one end with the outlet 17 of the suction fan and opens at its other end into a pervious bag 18 connected to the rear end of the tube; the mouth of the tube being provided with a suitable gate 19 to prevent the return of dust into the machine.

A larger pervious bag 20 preferably surrounds the dust bag 18, and its mouth is connected to the rear end of the cylindric extension 3 of the fan casing and communicates through the same to the inlet opening 21 of the blast fan.

The blast fan 6 and the suction fan 7 are driven by the motor 4, and the latter fan creates a suction in the mouth 9 of the machine which draws the air either through the carpet or under the lips 10 and 10' of the mouth; and the dust laden air is discharged into the dust bag 18, the air passing through the pervious wall thereof into the larger pervious bag 20.

At the same time the smaller blast fan draws air from the larger bag and discharges the same as a blast through the channel 12 in the head of the machine, and thence under the edge of the partition 11 therein to scour or to sweep the objective surface, whence this air joins the larger current of air which is drawn through the larger channel 13 and the suction fan.

The excess of air moved by the suction fan passes through the outer pervious bag 20, so that the air returned by the blast fan does not break the vacuum or suction created by the larger fan; and it is evident that the outer bag 20 catches the dust which is not caught by the inner bag and serves as a second settling container bag for the dust.

In Fig. 2 the stronger suction fan 7^b is located above the smaller blast fan 6^b and communicates with the forward channel 12^b in the head of the machine which is larger than the rear channel 13^b communicating

with the discharge opening of the blast fan 6^b, so as to reverse the direction of the blast of air passing under the edge 11^b of the single transverse partition walls 11^b in the head. Otherwise the general arrangement and operation of the machine is the same as shown and described for Figure 1.

I claim:

1. A suction cleaner including a head with an elongated mouth and contact lips, a division within the mouth adjacent and above the plane of the lips forming slots on opposite sides thereof, means for impelling a current of air into the mouth through one of the slots for sweeping an objective surface, and means impelling a greater volume of air from the mouth through the other slot

for suction cleaning through the elongated mouth.

2. A suction cleaner including a head with an elongated mouth and contact lips, a division within the mouth adjacent and above the plane of the lips forming slots on opposite sides thereof, an impeller discharging air into the mouth through one of the slots for sweeping the objective surface, a second stronger impeller drawing air from the head through the other slot for suction cleaning through the mouth, a pervious dust bag into which the second impeller discharges and a second pervious bag around the first bag communicating with the inlet of the first impeller.

ADAM A. SERVA.
